UNITED STATES PATENT OFFICE.

HAROLD BROWN, OF KANSAS CITY, AND GEORGE R. UHL, OF TONGANOXIE, KANSAS.

AIR VALVE.

Application filed February 23, 1926. Serial No. 90,181.

- This invention relates to an improved air valve particularly adapted for the cylinder of air brakes commonly used in connection with railroad cars.
- 5 It is to be understood that the air valve provided in this invention may be used on other cylinders of suitable type without departing in any degree from the spirit of this invention.
- 10 Various objects of this invention will appear in the following detailed description of the device and as disclosed in the two sheets of drawings which is herewith made a part of the application.
- 15 In the drawings, similar numerals of the different views represent the same element.
- Fig. 1 illustrates a sectional side elevational view of an air valve.
- Fig. 2 represents a vertical sectional view 20 showing the lever arm in operative position, the view being taken along the line 2—2 of Fig. 1.
- Fig. 3 illustrates a sectional elevational view of a modified form of air valve over 25 that disclosed in Fig. 1 and showing the relationship of the lever arm thereto. Numeral 38 designates a section of the exhaust port in the valve construction.
- Fig. 4 represents a plan view of the guide 30 and support for the spring disclosing the air passage therethrough.
- Fig. 5 represents a plan view of a modified form of lever.
- Fig. 6 illustrates a plan view of a modified 35 form of lever over the forms disclosed in Figures 3 and 5.
- Figures 7 and 8 illustrate further modified forms of air valves adapted for the cylinder of air brakes commonly used in connection 40 with railroad cars.
- Numeral 1 designates the housing of an air valve for brakes commonly used for instance, on railroad cars, while numeral 11 45 designates the valve stem having a valve portion 6 adapted to be held in tension or in position within the cylinder by means of spring 5, the spring 5 being guided and supported by the means of a plate 2 having suitable openings 3, adapted to allow the free passage of air therethrough. An operating lever arm 7 is adapted to be positioned in interlocked relationship with the housing 1 of the air valve and the piston 4 by means of suitable pins 8 and 9.
- Fig. 1 discloses a modified form of air 55 valve having a housing 10, a stem 11, a valve 12 and tension spring 13, the operating lever 14 being clearly disclosed in Fig. 2 in interlocked relationship with the housing 10 by means of pins 15 and 16. The lever arm 60 17 disclosed in Fig. 5 is slightly modified in construction over the levers disclosed in Figures 2 and 3, in that, when lever 17 is operated by pulling in either direction, it rocks in slots 18 and 19, instead of notches 20, 21, 65 22, and 23.
- Fig. 6 illustrates a slightly modified form of levers 24, over the levers disclosed in Figures 2, 3 and 5, in that the slots 25 and 26 are horizontal. 70
- Fig. 7 designates the modified form of air valve having a housing 27, a tension spring 28, a valve portion 29, and a valve stem 30 adapted to be operated by means of operating lever 31 positioned in interlocked 75 relationship with the housing 27 by means of pins 32 and 33.
- Fig. 8, represents a further modification 80 of an air valve 34, and the operating lever arm 35, the tension spring 36, in this case being located above the valve 37.
- In operation, this invention provides a simple improved air valve for cylinders, inexpensive to manufacture, and easily operated, particularly as applied to the air release for the cylinder of air brakes now 85 commonly used on railroad cars. At the present time, in the operation of bleeding air brake cylinders, it is a common practice to bleed the cylinder or car, before cutting loose from the engine, as for instance, in switching. To accomplish this, a member 90 of the train crew pulls a lever and holds it from half a minute to 3 minutes or more for each car switched. 95
- One of the principal objects of this invention is to provide mechanical means for releasing the air in a few seconds, thereby saving the time of the train crew and materially expediting the work of the train 100 switching. The practice is, when cutting a car loose from an engine, to pull a lever and hold it until the air is released, while this invention makes it possible to release the air valve by a simple turn or pull of a rod 105 in a few seconds. Obviously, valuable time of the whole train crew is therefore saved.

What we claim is:

In an air releasing device, a casing, a valve seat portion and a stem for the seat portion slidably positioned within the casing, a spring tension means for the seat portion, means for guiding the stem and supporting the spring, consisting of a plate suitably positioned within the casing, the plate being provided with air ports, and means for depressing the stem, thereby releasing the valve. 10

In testimony whereof we affix our signatures.

HAROLD BROWN.
GEORGE R. UHL.
